INVENTOR:

William R. Monroe

By his attorney

Watson & Thurston

UNITED STATES PATENT OFFICE.

WILLIAM R. MONROE, OF CLEVELAND, OHIO.

FIRE-CURTAIN.

SPECIFICATION forming part of Letters Patent No. 445,337, dated January 27, 1891.

Application filed February 17, 1890. Serial No. 340,737. (No model.)

To all whom it may concern:

Be it known that I, WILLIAM R. MONROE, a citizen of the United States, residing at Cleveland, in the county of Cuyahoga and 5 State of Ohio, have invented a certain new and useful Improvement in Fire-Curtains, of which the following is such a full, clear, and exact description as will enable others skilled in the art to which it appertains to make and 10 use the same.

My invention relates to that class of devices commonly known as "fire-curtains," which are designed to protect life and property by confining a fire which may break out 15 in a building within certain narrow limits.

The object of my invention is primarily to render the action of such fire-curtains automatic, whereby they will not depend for 20 their efficiency either upon the watchfulness of any person or the ability of any one to reach them and arrange them properly in time of need, and also to provide means whereby they may be operated by hand, if there should be time.

25 To this end it consists in the construction of parts hereinafter described, and pointed out definitely in the claims.

In the drawings, Figure 1 is a front elevation of my invention properly arranged and 30 ready for use, and Fig. 2 is a vertical sectional view on line 2 of Fig. 1.

Referring to the parts by letter, A represents a curtain made of pivoted metallic slats, woven asbestos, or any other suitable 35 fire-resisting material, arranged above the window it is designed to close, and secured at its upper edge to a roll C, which roll is mounted in suitable bearings. The curtain is rolled upon this roll by hand, or, if desired, by any suitable mechanism, and, when 40 permitted, unrolls by gravity. It is prevented from thus unrolling by the vertically-placed fusible pin B, which engages with a bracket D and with a socket in the roll C.

45 In order to provide means whereby the curtain may be lowered before the pin B is melted, the brackets E E' are provided with loose bearings for the roll C, a lever F is pivoted in proper relation to the roll, and attached to one end of this lever is a block G, 50 in which is formed a bearing for one end of

the roll. By means of the lever F the roll is lifted from its bearing in the bracket E' to the position shown in the drawings, where when released by the fusion of the pin B it 55 turns in its bearings in the bracket E and block G. The lever F is held in this position by means of the cord or rope H, which is fastened at any convenient point. When the roll is in the above-described position, the 60 fusible pin B engages in the socket of the roll, thereby preventing its revolution; but when the cord H is unfastened the end of the roll C drops into the bearing in the bracket E', thereby disengaging the roll from 65 the pin B and permitting said roll to turn freely in the brackets E and E', whereby the curtain falls.

The above-described invention may be placed over doors connecting different parts 70 of a building, and thus assist in preventing the spread of a fire. The curtains may be placed around elevator-shafts, or in such position as to fall across elevator-shafts at floor-levels. They may also be placed over windows, especially such as are adjacent to the fire-escape ladders, whereby the escape down 75 said ladders may not be cut off by the flames and heat from the windows on the lower floors. They may, in short, be placed in any 80 position where fire-curtains are desirable, with these marked advantages: first, that they will act automatically, and, second, that, in addition to that, they may be operated by hand, if there is time.

Having thus described my invention, what I claim as new, and desire to secure by Letters Patent, is—

1. The combination of a fire-resisting curtain, a roll to which said curtain is secured, 90 brackets secured above the opening the curtain is designed to close, bearings in said brackets in which the roll is mounted, a stationary bracket, a socket in the roll, and a pin of easily-fusible alloy which engages with 95 said bracket and socket, substantially as and for the purpose specified.

2. The combination of a fire-resisting curtain, a roll to which said curtain is secured, brackets secured above the opening the curtain is designed to close, loose bearings in 100 said brackets in which the roll is mounted,

with a pivoted lever having secured to one end a bearing-block, in which one end of said roll is journaled, a stationary bracket, a socket in the roll, a pin of easily-fusible alloy which 5 engages with said bracket and socket, and mechanism for holding said lever in the position necessary to continue the engagement

of said fusible pin with said bracket and socket, substantially as and for the purpose specified.

WILLIAM R. MONROE.
